HOT STICK

Ellis D. Currey, Phoenix, Ariz.

Application October 9, 1950, Serial No. 189,100

3 Claims. (Cl. 140—93)

1

This invention concerns hot sticks, used to work on and about energized high tension transmission lines.

Heretofore, rubber gloves have been used by linemen up to the limit of their protection. However, many lines now exceed the safe voltages for these, and various devices have been improvised for attaching the lines to insulators, replacing broken insulators and the line. One of the most important functions of a hot stick is to secure an energized line wire to an insulator by means of a tie wire and to remove tie wires from insulators so that the line wire may be removed.

One of the objects of my invention is to provide a hot stick which may be easily handled and will hold, position and twist a tie wire on a line wire to hold it on an insulator, and will untwist the wire and remove it when desired;

Another object is to provide a hot stick having a rotary twisting element which may be applied to a line wire and will then engage a tie wire and wrap or twist it around the line wire, so as to secure it to the insulator quickly, accurately and with a minimum of effort on the part of the user;

Still another object is to provide a hot stick which may be applied to an energized line wire and locked in place so the wire may be safely moved or lifted from the insulator and held while a new insulator is installed.

Other objects will appear hereinafter.

I attain the foregoing objects by means of the combination of the peculiarly and specially formed devices and combination of parts illustrated in the accompanying drawings, in which—

Figure 1 is a perspective view of the hot stick as it is used in applying a tie wire to a line wire resting in an insulator;

Figure 2 is a side view of the head mechanism of the hot stick drawn on an enlarged scale;

Figure 3 is an edge view thereof;

Figure 4 is a sectional view of the rotary twisting portion of the mechanism drawn on a somewhat reduced scale;

Figure 5 is a perspective view of a fragment of the outer portion of the twisting mechanism showing the means of holding a tie wire;

Figure 6 is a plan view of an insulator carrying a line wire held in place by a twisted tie wire;

Figure 7 is a perspective view of the head mechanism applied to a line wire and brought into engagement with the tie wire; and

Figure 8 is a similar perspective view of showing the head upon the completion of a twist on one side of an insulator.

Similar numerals refer to similar parts in the several views.

2

The hot stick consists in general of a wooden pole or handle 2, which is dried and coated with shellac to insure insulating qualities; a head 3 which includes twisting mechanism 4, an operating chain 5, a rope 6, joining the lower ends of the chain and a pulley 7, supported in take-up tightening mechanism 8, near the bottom of the pole. These parts are illustrated in Figure 1 where a break is shown in the pole and rope to indicate that these parts may be of any desired lengths.

At the upper end of the pole there is the head 3 which is attached by ferrule 12. This, in turn, supports plate 14, which has a U-shaped bend 11 at the top to enclose idler sprocket 16 which is journaled on shaft 18. Below this and at the lower or right hand edge of plate 14, as viewed in Figure 2, rotary twisting mechanism 4 is supported on a split hollow shaft 20 which is welded to plate 14 at its inner end as shown by numeral 15 in Figure 4. The split or longitudinal slot 22 in this shaft opens angularly downward and slightly outward as shown in Figure 2. The lower edge 23 of plate 14 joins the inner edge of this slot. The width of the slot is about one half the diameter of the shaft. An annular retaining ring 25 is formed on the inner end of shaft 20 and is similarly slotted. Spindle 27 is journaled on shaft 20 and is retained by ring 25 at the outer end and by plate 14 at its inner end. It has a longitudinal slot 28 of the same width as slot 22 in shaft 20. A twisting sprocket 30 is welded to spindle 27 near its inner end and is provided with slot 32, radially aligned with spindle slot 28.

An arcuate twisting hook 34 is welded to the inner end of spindle 27 on a spacer hook 36. Two horns 37 and 38 are provided so that the hook will engage loops of a tie wire when rotated in either direction. Hook 34 is attached to the spindle at a position opposite to its slot 28.

A chain 5 is attached at one end to one end of rope 6 by clevis 42. It runs upward over idler sprocket 16 and downward against twisting sprocket 30. The teeth on the inner portion of this latter sprocket engage chain 5 on its outer face. The end of the chain below sprocket 30 is then attached to the other end of rope 6 by a clevis 44. A hooklike stop 46 attached to plate 14 engages clevis 44 which acts as a stop lug and limits upward motion of the end of the chain to which it is attached. This stop is positioned so that, when clevis 44 engages the slot 32 in twisting sprocket 30 and the slot in spindle 27 will be aligned, or in register, with the slot 22 in shaft 20. The twisting mechanism may then be said to be open, and all slots will receive line wire 50.

Rope pulley 7 is supported in pulley block 49 which has a downwardly extending screw and may be drawn downward by thumb nut 48. This constitutes the tightening mechanism 8.

The principal use of this hot stick is to rapidly and tightly twist tie wires such as 52, Figs. 6, 7 and 8, onto line wires 50 to secure the line wire to an insulator 54. Heretofore, this twisting has been done very slowly, one half turn at a time, by a hot stick to which was attached a compound hook known as a mechanical hand. With my device, end loop 56 of U shaped tie wire 52 is grasped in the slot 28 of shaft 20 and held by partial rotation of spindle 27 as shown in Figure 5. Notches 53 oppositely positioned in the adjacent edges of these slots aid in holding the tie wire. Rotation is counterclockwise and is produced by a downward pull on the lay 58 of rope 6 which connects clevis 44, as shown in Figure 1. Tie wire 52 is then lifted above and to the right of insulator 54 and the free end hooked over the line wire at the top of the insulator. The head 3 is then moved downward and under insulator 54 and upward around the far side of the insulator, as shown in Figure 1, in a path indicated by dotted line 59. This brings the tie wire over the top of the insulator and across the top of line wire 50 and under the line wire so that the grasped portion 56a will lie in the left hand portion of the insulator groove 60. The head 3 is then further manipulated to bring the end of the tie wire adjacent its loop 56 under the line wire on the right side of the insulator. Loop 56 is then released and occupies the position shown in Figure 7. Loop 62 at the opposite end of tie wire 52 is then pushed under the line wire on the left side of insulator 54 and the horn 37 of hook 34 engaged in loop 62 as shown in Figure 7. The twisting mechanism 4 is maintained at open position and is then placed over line wire 50. A downward pull on rope lay 58 will then rotate sprocket 30 and hook 34 in a counterclockwise direction, as viewed in Figure 8, or so that the left end of tie wire 52 is rotated and twisted clockwise around line wire 50 when the insulator is viewed along the line wire from the left side. The finished twist then appears as shown adjacent tie wire loop 62, Figure 6. A reversal of the direction of rotation of hook 34, by a pull on the lay 58a of rope 6, opposite 58, will release the hook from loop 62.

The head 3 is then positioned so that twisting mechanism 4 faces line wire 50 on the right side of insulator 54. The mechanism 4 is moved to open position and horn 37 of hook 34 engaged in loop 56. The slots 32, 28 and 22 being in register, are hooked over the line wire. A pull on rope lay 58 will now twist the end of tie wire 52 adjacent its loop 56 clockwise when viewed in a direction toward the insulator. The hook is again disengaged and the completed tie appears as in Figure 6.

The tie wire may be removed by a reversal of the last portion of the above operation. The horn 38 of hook 34 will engage either of the loops 56 or 62. The twisting mechanism in open position is first hooked over line wire 50 with the hook 34 adjacent the insulator, the twisting mechanism is rotated in a reverse direction to the twist of the tie wire and the parts held so that the hook engages the tie wire loop. Continuation of this rotation then untwists the tie wire. The twist on the opposite side of the insulator is then removed in a similar manner.

When it is desired to lift the line wire 50 from

the insulator the mechanism 4 is moved to open position and the slots in registering position hooked over the line wire. Rotation of sprocket 30 and spindle 27 one half turn effectively closes the slot 28 and the line wire cannot get away from the head 3. By using pole 2 as a lifting handle the line wire 50 may be raised from the insulator and swung to either side, as desired.

From the foregoing it will be seen that pole 2 constitutes an extended insulating handle by means of which energized or "hot" line wires may be handled or worked on by the mechanism composing head 3. This head is supported on a metal frame which includes the plate 14, the U shaped top 11, and the attaching ferrule 12.

The twisting mechanism 4 operates on this frame. This mechanism rotates on the slotted shaft 20 as a stationary supporting part, and a rotating twisting element which includes the slotted spindle 27, the slotted sprocket 30 on its inner end, adjacent plate 14, and the double pronged hook 34 on its outer end. This rotating twisting element is given rotary motion by manually operated mechanism including the chain 5, the supporting or idler sprocket 16 and rope 6.

The whole device, therefore, consists of four main parts, the pole, as an extended means of support; the frame and its slotted shaft as the basis of a line engaging hook; the rotating twisting element; and the chain and rope as a means for rotating the twisting element from the lower end of the hook.

By placing the slotted rotating element so that it rotates around the slotted shaft means are provided for twisting or untwisting any loops or parts of wires which may be engaged by hook 34. The slots in the shaft and spindle when in register and open form a hook slot to receive line wire 50, which may be closed by a half turn rotation of the rotating element; and the edges of the slots may be used to grip and releasably hold tie wires, as shown particularly in Figure 5.

The use of the slots in the respective parts, as above explained, is possible only when chain 5 runs over the back or inside portion of sprocket 30. Obviously, the outer portion must be left open.

Many modifications and mechanical equivalents may suggest themselves to those familiar with the art. Therefore, I wish to be limited only by the claims.

I claim:

1. A hot stick for applying tie wires having attaching loops at each end to energized line wires held on insulators, comprising in combination, an insulated supporting pole adapted to be held at the lower end thereof, a frame at the top end thereof, an idler sprocket journaled on a shaft at the top of said frame; twisting mechanism in the lower portion of said frame composed of a hollow shaft attached at its inner end to said frame extending parallel to said idler sprocket shaft having a longitudinal slot opening downward and angularly slightly outward, a sprocket mounted on a hollow spindle journaled on said shaft, both sprocket and spindle having a longitudinal slot adapted to register with said slot in said shaft so that a line wire may be introduced into said hollow shaft through said slots when in register, and a tie wire engaging hook attached to said spindle adjacent the outer end thereof, and opposite said slot, having projecting horns extending partially around said spindle, adapted to engage a tie wire loop when rotated in either direction;

and means for rotating said slotted sprocket from the lower end of said pole including a chain running over said idler sprocket and against the inner portion of said slotted sprocket, and attached at its lower ends to an insulating rope looped over a pulley near the lower end of said pole; and means for stopping the turning movement of said twisting sprocket with the slots in said sprocket and spindle in register with the slot in said shaft, including a clevis on said chain and a stop on said frame adapted to engage said clevis.

2. A hot stick for applying tie wires having loops at each end to energized line wires held on insulators, comprising in combination, an insulated supporting pole adapted to be held at the lower end thereof, a frame at the top end thereof, an idler sprocket journaled on a transverse shaft at the top of said frame; twisting mechanism in the lower portion of said frame composed of a hollow stationary shaft transversely attached at its inner end to said frame, extending parallel to said idler sprocket shaft, having a longitudinal slot opening downward and angularly slightly outward; a radially slotted sprocket mounted on a hollow slotted spindle journaled on said stationary shaft having a longitudinal slot adapted to register with said slot in said stationary shaft so that a line wire may be introduced into said hollow shaft through said slots when in register; and a tie wire engaging hook attached to said spindle adjacent the outer end thereof opposite the slot therein, having projecting horns spaced from the surface thereof and extending arcuately partially around said spindle adapted to engage the end loops of a tie wire when rotated in either direction; a chain running over said idler sprocket and with its outside engaging the teeth of the inner portion of said slotted sprocket and attached at its lower ends to the upper ends of an insulating rope looped over a pulley journaled on a transverse shaft near the lower end of said pole.

3. A hot stick for applying tie wires having loops at each end to energized line wires held on insulators, comprising in combination, an insulated supporting pole adapted to be held at the lower end thereof, a frame at the top end thereof, an idler sprocket journaled on a transverse shaft at the top of said frame; twisting mechanism in the lower portion of said frame composed of a hollow stationary shaft transversely at-

tached at its inner end to said frame extending parallel to said idler sprocket shaft, having a longitudinal slot opening downward and angularly slightly outward; a radially slotted sprocket mounted on a hollow slotted spindle journaled on said stationary shaft having a longitudinal slot adapted to register with said slot in said stationary shaft so that a line wire may be introduced into said hollow shaft through said slots when in register; and a tie wire engaging hook attached to said spindle adjacent the outer end thereof opposite the slot therein, having projecting horns spaced from the surface thereof and extending arcuately partially around said spindle adapted to engage the end loops of a tie wire when rotated in either direction; a chain running over said idler sprocket and with its outside engaging the teeth of the inner portion of said slotted sprocket and attached at its lower ends to the upper ends of an insulating rope looped over a pulley journaled on a transverse shaft near the lower end of said pole; means for maintaining a tension on said rope and chain including a pulley block housing supporting said rope pulley attached by a screw to a bracket on said pole, and having an adjustable thumb nut thereon below said bracket; and means for stopping the turning movement of said twisting sprocket at a position with the slots in said sprocket and spindle in register with the slot in said shaft, including a clevis on said chain and a stop bracket on said frame adapted to engage said clevis.
